UNITED STATES PATENT OFFICE.

JOHN SPENCE, OF LETHBRIDGE, ALBERTA, CANADA.

GATE-OPENING DEVICE.

1,079,449.

Specification of Letters Patent.

Patented Nov. 25, 1913.

Application filed April 12, 1912. Serial No. 690,291.

To all whom it may concern:

Be it known that I, JOHN SPENCE, of the city of Lethbridge, in the Province of Alberta, Canada, have invented certain new and useful Improvements in Gate-Opening Devices, of which the following is the specification.

My invention relates to a device for opening gates, and the object of the invention is 10 to provide an inexpensive, easily operated, and durable device of this class.

With the above object in view the invention consists essentially in the arrangement and construction of parts hereinafter more 15 particularly described and later pointed out in the appended claims.

Figure 1 is a side elevation of the complete device attached to a gate. Fig. 2 is an end view of the same. Fig. 3 is a plan view. 20 Fig. 4 is an enlarged detailed plan view of the locking bar. Fig. 5 is an enlarged detailed side view of the rollers carried by the top cross beam. Fig. 6 is a sectional view through the track secured to one of the 25 fence boards. Fig. 7 is a sectional view through the track carried by the spanner.

In the drawings like characters of reference indicate corresponding parts in each figure.

30 1 and 2 represent upright gate posts firmly embedded in the ground 3 and connected at the top by a spanner 4.

5 is a top beam secured centrally to one end of the spanner and having the ends 35 thereof supported by braces 6 and 7 which pass angularly between the cross beam and the post 1.

8 represents a fence post which is connected to the gate post by the usual fence 40 boards 9.

10 is a gate formed from inner and outer upright end beams 11 and 12 connected by cross bars 13. The beam 12 is considerably longer than the beam 11 and it is reinforced 45 by an angularly disposed brace beam 14.

15 is a track secured permanently to the upper of the fence boards 9, which track supports a roller 16 fastened to the upper end of the upright beam 11.

50 17 is a track secured permanently to the spanner and supporting a roller 18 carried by a special casting 18' to the upper end of the upright beam 12. These rollers it will be seen support the gate so that it can be 55 shifted backwardly and forwardly as desired. The casting 18' presents a sheath for

the roller 18 and is supplied at the inner side with two opposing lugs 18² and at the outer side with a single lug 18³.

19 is a locking bar pivotally secured by a 60 pin 19' to the lugs 18² and having the free end more or less in the form of a spear point presenting notches 20 and 21. The body of the locking bar is provided with an opening 23 in which is located a roller 24.

65 25 is a spring pressed latch pivotally fastened at 26 to the gate and having the forward end designed to pass over a pin 27 secured to the post 2.

70 "A" is a ring located directly under the locking bar and carried by two cables 28 and 29 which pass upwardly through the opening 23 over the roller 24 around pulleys 31 located on the under side of the top beam 5, after which they are passed in opposite 75 directions outwardly over further pulleys 32 located at the end of the cross beam 5. The ends of the cables are supplied with hand grips 33 and 34 respectively, while weights 35 are tied to them between the pulleys 32 and the hand grips.

75 A wire "B" connects the ring "A" with the spring latch 25. The ring "A" is supplied large enough so that it will not pass through the opening 23 in the locking bar 80 and it is positioned sufficiently far below the locking bar to allow the cables to release the spring latch 25 prior to the ring engaging with the locking bar.

85 36 is a dividing plate appearing between 90 the pulleys 31, and 37 are short catch rods located at each side of the plate toward the pulleys, which catch rods are designed to enter the notches 20 and 21, respectively, depending on the position of the locking bar. 95 It will at this point be readily seen that if one pulls on one or other of the cables 28 or 29 he will first lift the latch 25 to release the gate and then he will swing the catch bar to one side or other so that the catch bar 100 will lock the gate open as soon as it engages with one or other of the catch rods 37.

105 38 is a cable or rope tied to the lug 18³ and passing over a pulley 39 carried by the post 3. The free end of said cable carries a weight 40 sufficiently heavy to draw the gate closed when the catch bar is released.

110 The operation of the attachment is now described assuming a person approaching the gate in a vehicle and that the gate is closed. At the time the driver comes within range of the first hand piece he grabs it and

pulls, which action causes the gate to be opened, the pulled cable initially raising the latch and finally drawing the gate over so that the locking bar engages with one of the catch pins. When this occurs the cable can be released as the gate is locked open and the vehicle can then pass through the gate opening. Upon reaching the opposite side he grasps the other hand grip, which action causes the locking bar to pass away from the catch pin. The hand grip can then be released and the gate will close of itself, being drawn by the weight 40.

In order to prevent the bottom of the gate from swinging sidewise I have secured a bracket 41 to the base of the post 1. Two stops 42 are also fastened to each side of the post 2 and receive the outer end of the gate when it is closed assisting the latch in holding it firmly.

20 What I claim as my invention is:—

1. The combination with a gate and tracks supporting the gate, of weighted means holding the gate normally closed, hand grips connected to the gate and located at the approach to and beyond the same, and means for locking the gate in the open position, said latter means being set in the locking position by a pull on the hand grip on the approaching side of the gate and released from the locking position by a pull on the hand grip located beyond the gate, as and for the purpose specified.

2. The combination with a gate, a track supporting one end of the gate and located at the end thereof, and an elevated track supporting the other end of the gate and located above the same, of weighted means designed to continuously close the gate, releasable means for locking the gate in the open position, elevated hand grips at the approach to and beyond the gate, such hand grips being connected by cables with the locking means, said locking means being arranged to be set in the locking position by a pull on the hand grip on the approaching side of the gate and released by a pull on the hand grip beyond the gate, as and for the purpose specified.

3. The combination with a pair of upright gate posts, a spanner connecting the posts at the top, a gate, and a track located at the side of one of the gate posts and supporting the adjoining end of the gate, an elevated track secured to the spanner and supporting the other end of the gate, a pulley adjoining the latter end of the gate, a weighted cable secured to the gate and passing over the pulley, releasable means for locking the gate in the open position, elevated hand grips located at the approach to and beyond the gate, such hand grips being connected with the locking means and arranged to control the setting and releasing of said locking means upon

the hand grips being pulled, as and for the purpose specified.

4. The combination with a pair of upright gate posts, a spanner connecting the posts at the top, a gate, and a suitably braced elevated cross beam located at the upper end of one of the posts, of an extending track located to the side of the latter gate post and supporting the adjoining or inner end of the gate, an elevated track carried by the spanner and supporting the other or outer end of the gate, a pulley carried by the gate post adjoining the outer end of the gate, a weighted cable secured to said end and passing over the pulley, a notched locking bar pivotally secured to the gate, elevated hand grips suspended from the ends of the cross beam at the opposite sides of the gate and connected through suitable cables with the locking bar, and a set of catch rods carried by the cross beam designed to enter the notches in the locking bar, as and for the purpose specified.

5. The combination with a pair of upright gate posts, a spanner connecting the posts at the top, a gate, and a suitably braced elevated cross beam located at the upper end of one of the posts, of an extending track supporting the inner end of the gate, an elevated track secured to the spanner and supporting the outer end of the gate, a pulley carried by the gate post adjoining the latter end of the gate, a weighted cable passing over the pulley and secured to the outer end of the gate, a notched locking bar pivotally secured to the outer end of the gate, pulleys located at the extending ends of the cross beam, a set of pulleys carried by the cross beam and adjoining the gate post, locking rods carried by the cross beam and adjoining the latter pulleys, such rods being designed to pass into the notches in the locking bar, cables passing over the pulleys carried by the cross beams and connected with the locking bar, and hand grips secured to the ends of the cables and located beneath the extending end of the cross beam, as and for the purpose specified.

6. The combination with a pair of upright gate posts, a spanner connecting the posts at the top, a gate, and a suitably braced elevated cross beam located at the upper end of one of the posts, of an extending track supporting the inner end of the gate, an elevated track secured to the spanner and supporting the outer end of the gate, a pulley carried by the gate post adjoining the latter end of the gate, a notched locking bar pivotally secured to the outer end of the gate, a weighted cable secured to the outer end of the gate and passing over the pulley aforesaid, pulleys located at the end of the cross beam, a set of pulleys carried by the cross beam and adjoining the post supporting the same, cables passing around the pulleys carried

by the cross beam, such cables having their inner ends passing to and through the locking bar, and their outer ends supplied with hand grips and weights, a ring secured to the inner ends of the cables, and locking rods carried by the cross beam adapted to pass into the notches formed in the locking bar, as and for the purpose specified.

7. The combination with a pair of upper gate posts, a spanner connecting the posts at the top, a gate, a spring-pressed latch carried by the gate, and a suitably braced elevated cross beam located at the upper end of one of the posts, of an extending track supporting the inner end of the gate, an elevated track secured to the spanner and supporting the outer end of the gate, a pulley carried by the gate post adjoining the latter end of the gate, a notched locking bar pivotally secured to the outer end of the gate and supplied with an opening in the bottom portion thereof, a roller

mounted in the opening, a weighted cable secured to the outer end of the gate and passing over the pulley aforesaid, pulleys located at the end of the cross beam, a set of pulleys carried by the cross beam and adjoining the post supporting the same, a ring, a wire connecting the ring with the latch, cables passing over and around the pulleys carried by the cross beam and having their inner ends connected to the ring and their outer ends supplied with weights and suitable hand grips, such cables passing through the opening provided in the locking bar and over the roller, as and for the purpose specified.

Signed at Lethbridge this 24th day of November, 1911.

JOHN SPENCE.
